INVENTOR,
William E. Thoroman,
BY
Howard S. Smith,
2/2 ATTORNEY

UNITED STATES PATENT OFFICE

WILLIAM E. THOROMAN, OF NEAR DAYTON, OHIO

FLAG SUPPORT AND RAISER

Application filed June 9, 1930. Serial No. 460,006.

This invention relates to new and useful improvements in flag supports and raisers.

It is one of the principal objects of my invention to provide a flag support which does not require a raising pulley at its top but instead provides a vertical track along which a flag carrying member, propelled through its engagement with the track, travels when a chain is pulled.

10 Flag poles of the conventional type having fixed pulleys at their top, require the erection of scaffolding to remove or repair these pulleys when they break. This is expensive and time consuming. In my construction, on the other hand, the flag holder travels up and down the fixed track in response to the pull exerted upon an endless chain which operates the track engaging mechanism carried by the holder.

20 Other important and incidental objects will be brought out in the following specification and particularly set forth in the subjoined claims.

In the accompanying drawings illustrating 25 my invention, Figure 1 is a side view of the flag support attached to a flag pole, with the movable flag carrier in its top position. Figure 2 is a detail view of the track and holder, with the former in section and the latter partly broken away and in section. Figure 3 is a sectional view taken on the line 3—3 of Figure 2. Figure 4 is a cross sectional view taken on the line 4—4 of Figure 2. And Figure 5 is a sectional view taken 35 through a steel pole to which a flat track is secured.

Referring to the accompanying drawings for a detailed description of my invention, the numeral 1 designates a flag pole mounted 40 on a base 2. Secured to the pole 1 by screws 3 is a channel track member 4 which projects downwardly from the top of the pole to a point a short distance above its base 2.

45 Formed in the flat side portions of the track 4, along the longitudinal marginal edge of each, are holes 5. Adapted to engage in these holes are teeth 6 on toothed wheels 7, 7 fast on a shaft 8 whose ends project through holes in the right angle sides 9, 9 of a channel member 10. The latter has guide flanges

11, 11 that travel along the marginal edges of the track.

Attached by screws 12 to the back part of the channel member 10 is a flanged member 13. To the flange 14 on the latter and to the right side 9 of the channel member 10, the inner side 14^a of a sprocket housing 15 is secured. This side 14^a has a top semi-circular end as shown in Figure 2.

55 Formed on the side 14^a of the sprocket casing 15 is an outwardly turned flange 16 to which a flange 17 on the outer side 18 of the casing 15 is secured. Within the casing 15 as thus constructed a sprocket wheel 19 is secured to the shaft 8.

60 The casing 15 is open at its bottom for the reception of an endless sprocket chain 20 which passes around the sprocket 19. The lower run of this chain is received by a receptacle 21 attached by bands 21^a, 21^b to the bottom of the pole 1 and provided with a hinged lid 22. Secured to the pole 1 just above the receptacle 21 is a pin 23 around which the chain may be wrapped to maintain the flag holder in its uppermost position.

65 The upper inner corner portion of a flag such as the flag 24 shown in dotted lines in Figure 1, is attached to an inverted U-shaped piece 25 secured to the flanged member 13. To the lower inner corner of the flag there is 70 secured a ring 26 through which the chain is 75 free to pass.

When it is desired to raise the flag, the chain 20 is pulled by the hands to turn the toothed wheels 7, 7 in a direction which will cause them to travel up the track 4 to carry the holder, to which the flag is attached, upwardly. And when it is desired to lower the flag, the toothed wheels 7, 7 are rotated in the opposite direction by the chain. The 80 movable flag carrier, raised and lowered through the engagement of its toothed wheels with the stationary track 4, thus becomes an effective substitute for a fixed pulley at the top of the pole. Always at the bottom of the 85 latter when the flag is lowered, the movable carrier is accessible at all times for adjustment and repair without the necessity of erecting a scaffolding to reach it.

90 A track of channel section such as the track 100

4, is employed where the pole bends easily or is of a weak construction, to reinforce it. In the case of a strong pole like the steel pole 27 in Figure 6, a straight track member, such as 6 the track member 28, may be used.

Having described my invention, I claim:

1. A device of the type described, comprising a track member attachable to a flag pole, a flag carrier adapted to travel up and 10 down said track member, mechanism contained within the carrier for engagement with the track member to propel it along the latter, and a chain depending from the carrier for operating said mechanism to raise and lower 15 said carrier.
2. A device of the type described, comprising an apertured track member attachable to a flag pole, a flag carrier adapted to travel up and down said track member, a 20 toothed wheel secured to the carrier for engagement with the apertures of the track member to propel it along the latter, a sprocket also on the flag carrier, and operatively connected to the toothed wheel, and an 25 endless chain depending from the sprocket for turning the latter to raise and lower said carrier.
3. A device of the type described, comprising a wide track member formed with 30 two parallel rows of equally spaced holes extending from top to bottom, a channel housing free to travel up and down said track member, a shaft journaled in said housing, a pair of toothed wheels secured to said shaft, 35 the teeth on said wheels free to enter said holes, a sprocket secured to said shaft, and an endless chain passing around the sprocket and depending therefrom through the housing for the purpose specified.
- 40 4. A device of the type described comprising a wide track member formed with two parallel rows of equally spaced holes extending from top to bottom, a channel member free to travel up and down said track 45 member, a shaft journaled in said channel member, a pair of toothed wheels secured to said shaft, the teeth of said wheels adapted to enter said holes, a sprocket casing open at its bottom, on one side of the channel member, a sprocket in said casing attached to said shaft which projects into the casing, and an 50 endless chain passing around the sprocket and depending therefrom through the open end of said casing for the purpose specified.
- 55 In testimony whereof I have hereunto set my hand this 6th day of June, 1930.

WILLIAM E. THOROMAN.
